UNITED STATES PATENT OFFICE.

OTTO G. ZERSE AND SILAS T. YOUNT, OF LAFAYETTE, INDIANA.

VAGINAL SYRINGE.

SPECIFICATION forming part of Letters Patent No. 404,762, dated June 4, 1889.

Application filed September 24, 1888. Serial No. 286,254. (No model.)

To all whom it may concern:

Be it known that we, OTTO G. ZERSE and SILAS T. YOUNT, of Lafayette, in the county of Tippecanoe and State of Indiana, have invented certain new and useful Improvements in Vaginal Syringes; and we do hereby declare that the following is a full, clear, and exact description thereof, reference being had to the accompanying drawings, and to the letters of reference marked thereon, which form part of this specification.

This invention is an improvement in vaginal syringes, and its object is to improve the construction of the drainage-bulb by providing it with a distending annulus; and it consists in the hereinafter-described novel construction of such annulus and in the combination of parts hereinafter specified.

In the accompanying drawings, Figure 1 represents a perspective view of our improved device in connection with an ordinary bulb syringe, and Fig. 2 represents a longitudinal sectional view of our device detached from the syringe.

Referring to the drawings, the letter A indicates a tube of suitable dimensions, and constructed, preferably, of vulcanite or other poor conductor of heat and non-corrosive material. One end of the tube is bulbous in form or enlarged, as shown, and is provided with a series of perforations near its extremity, in order that the injected liquid may reach all parts of the internal mucous membrane. The tube at its opposite end is provided with a screw-threaded socket *a*, by which it is attached to the threaded connection of the syringe, as shown in Fig. 1 of the drawings.

The letter B indicates an oblong flexible drainage-bulb, constructed, preferably, of soft rubber. The said bulb at the forward end or portion to be applied to the vagina is provided with a large opening, in which is fitted an annulus *b*, of hard rubber or other suitable material, to keep the bulb distended at such point, so that the injected liquid may readily pass into the bulb, as more fully hereinafter described. In order that the annulus may be securely held in the opening, it is provided with an annular groove on its outside, into which the material of the bulb at the

edge of the opening springs, and the outer edge of the annulus is beveled or rounded, so as to fit the mouth of the bulb neatly and prevent injury to the vagina when the device is applied. The rear end of the bulb, directly opposite the large opening at the forward end, is provided with a smaller opening, of such size as to closely fit around the tube A and prevent leakage, while at the same time it will permit the tube to be adjusted longitudinally, so as to project to a greater or less extent through the large opening at the forward end and permit the tube to enter the vagina to any suitable extent in the treatment of diseases. The bulb is also provided with a small opening at one side, in which is fitted a short tubular connection *b'*, to which one end of a drainage-tube C is secured.

In using our improved device the tube is properly adjusted in the bulb, so as to project the desired extent from its forward end. The device is then inserted, the bulbous end of the tube and the forward end of the bulb entering the vagina, or the forward portion of the bulb may merely bear against the external parts of the labia. The injection is then effected in the usual manner, the reflux passing freely into the distended mouth of the bulb, escaping from the bulb through the drainage-tube.

As constructed it will be perceived that the device may be used with any suitable syringe, thus making it universal in application. Being extremely simple in construction, it may be readily cleaned and is comparatively inexpensive, and as the forward end of the bulb may be inserted into the vagina it may be used as a vaginal dilator by simply compressing the drainage-tube and at the same time pumping in the water, whereby the vagina may be thoroughly cleansed of pus and all abnormal discharges.

Having thus described our invention, what we claim, and desire to secure by Letters Patent, is—

The herein-described vaginal irrigator, consisting of a syringe, an injecting-tube A, enlarged and perforated in its front end, and having an enlarged screw-threaded flange *b* at its rear to connect with the syringe-tube, 100

with the drainage-bulb B on said tube tightly fitting the same at its rear end, but having a large orifice in its front end, the hard grooved annulus b, fitting in and distending the front orifice of the bulb, and the drainage-tube C, connected to bulb B, all substantially as and for the purpose specified.

5 In testimony that we claim the foregoing as

our own we affix our signatures in presence of two witnesses.

OTTO G. ZERSE.
SILAS T. YOUNT.
